SLING

Joseph M. Garris, Kenosha, Wis., assignor to
Macwhyte Company, Kenosha, Wis., a corpora-
tion of Wisconsin

Application December 3, 1937, Serial No. 177,943

12 Claims. (Cl. 96—25)

This invention relates to a sling and to the method of making it.

It has for one object to provide a sling formed of wire rope in which a part of the rope is 5 twisted and the remainder is braided or threaded back through the twisted part to form a sling in which there are four ropes extending the length of the sling.

Another object is to provide a method for 10 making such a sling, in which the sling, resulting from the method, is uniform in thickness and in the direction of braiding from end to end, so that the sling is free from irregularity and irregular twisting which might produce uneven or unsatisfactory wear.

Another object is to provide a sling formed of a 15 pair of members which is each twisted and in which the two parts thus partially twisted are placed together and braided or interwoven so that 20 the untwisted part of each is braided through the twisted part of the other.

Other objects will appear from time to time in the course of the specification and claims.

The invention is illustrated more or less dia- 25 grammatically in the accompanying drawings, wherein:

Figure 1 is an elevation illustrating a rope section before braiding or twisting;

Figure 2 is an elevation illustrating the same 30 section after twisting and before braiding;

Figure 3 is an elevation illustrating on an enlarged scale the member of Figure 2 after the 35 braiding has been partially completed;

Figure 4 is an elevation illustrating the com- 40 pleted sling after braiding is completed;

Figure 5 is a view generally similar to Figure 2 but showing the twisting extending not wholly from the end of the member but extending from a point spaced away from the end;

Figure 6 is an elevation generally similar to 45 Figure 4 but illustrating the completed sling in which the member 5 is used;

Figure 7 illustrates a further modified form 50 of the invention in which two original members are used and shows each twisted before braiding;

Figure 8 is an elevation illustrating the two members of Figure 7 placed together preparatory to braiding; and

Figure 9 is an elevation illustrating the com- 55 pleted braid.

Like parts are designated by like symbols throughout the specification and drawings.

As shown in Figure 1, a rope section or member A is bent, preferably centrally to produce two 55 halves 1 and 2. As shown in Figure 2, the mem-

ber A is placed over a pin or hook 3 for convenience in manufacture and has been twisted upon itself for roughly about one-half its length to produce a twist extending always in one direction. The twisting produces at approximately 5 the center of the rope section an initial eye B. As shown in Figure 2, the twisting produces a series of loops or openings 4, 4, 4. After the twisting has been carried out as far as is desired, the untwisted ends are bent across as shown in 10 the dotted line position of Figure 2 and are pushed through the first or lowermost of the loops or openings 4. In being thus bent, the rope end 1 produces a loop 5 and the rope end 2 produces a loop 6. When the bending is complete 15 and at the start or approximately at the start of the braiding, it is frequently convenient to attach a wire or cord 7 to hold the parts in place and for convenience in manufacturing.

For purposes of convenience, although the rope 20 member A, after having been bent or folded, is said to have formed two rope sections 1 and 2, that portion of each section which is bent upwardly for braiding or interlacing is considered as 1a and 2a respectively. Thus, that portion of 25 the total half 1 which is reversed to form the loop 5 is, as interlaced or braided, renumbered as 1a, and correspondingly that portion of the rope half or section 2 which is bent to form the loop 6 is renumbered as 2a above that loop. 30

Figure 3 shows on an enlarged scale the interlacing of the loops and the braiding of the rope sections. The rope section 1 crosses over the rope section 2, is bent to form the loop 5 and then in reversed direction passes upwardly, coming out 35 on top and passing through the first loop 4 downwardly, passing upwardly through the second loop 4 and downwardly through the third loop 4. The rope section 2 having passed below the rope section 1 is bent to form the loop 6, 40 passes through the loop 5 downwardly and comes out in the first loop 4, being numbered 2a at that point, swings to the left and passes downwardly through the second loop 4 and under the member 1a at that point, and then comes upwardly 45 through the loop 4. This process is repeated and is shown in the completed sling in Figure 4. The free or upper ends of the sections 1a and 2a are finally spliced together to form a second eye which lies parallel to the eye B and thus completes the sling. A wire or other fastening 8 may be put around the two eyes at the upper end of the sling as shown in Figure 4. 50

It will be noticed that in Figure 4 particularly there is no reversal of direction of the several 55

rope sections as they run from end to end of the sling itself. Each time the section 1a appears it crosses in the same direction and each time the section 2a appears it crosses in the same direction. Thus the sling is symmetrical from end to end and the wear on the rope sections, due to their positioning in the sling, is as nearly uniform throughout as possible.

In the form shown in Figures 5 and 6 the 10 rope section is the same as that of the other figures. A member A is bent to form two sections 9 and 10, and for convenience in manufacture it may be put over a pin or projection 3 as shown in Figure 2. This form of the sling, however, 15 differs from that of the first four figures by the fact that the twist begins at the center at which a center loop 11 is formed. By starting at the center of that portion of the sling which is to be twisted and twisting there, the result is that 20 the twisted portion is twisted equally but in opposite directions from the starting point. The method of braiding or interlacing the sling is generally the same in the form of Figures 5 and 6 as that described in connection with Figures 1 to 4 inclusive. As shown in Figure 6, the 25 lower end of the sling is substantially the same as that shown in Figure 4 except that the various sling parts cross over in the opposite direction. This is due to the direction of twisting caused by starting at the center at the loop 11. Except for this difference in direction, the lower 30 section of sling 6 is the same as that shown in Figure 4. When the sections 9 and 10 are reversed or bent upon themselves to start braiding, the section 9 forms a loop 12 and the section 10 forms a loop 13. At this point they may be attached together by a wire 14 or in any other manner. Starting from this end, the interweaving or braiding is, as above mentioned, carried 35 out in the same manner as shown in greater detail in Figures 3 and 4. When, however, the center of the twisted portion is reached because the twisting has run in opposite directions from the center, the direction of the braiding of the 40 members 9a and 10a must be changed. That is to say, the direction in which they cross is changed. For that reason, the members, instead of crossing when they reach the loop 11, pass straight or form what is known as a cross-over. 45 This is shown at the point X at the center of Figure 6. After this change of direction, which was necessitated by the change in the direction of twisting, has occurred, the braiding or interweaving continues in the same way and the sling 50 is completed, generally in the same manner as that shown in Figure 4. Wire or other fastening members 15 are used when the braiding is complete. The ends 9a and 10a are spliced together to form a loop which is interlaced with 55 the loop B and the sling is complete.

The sling thus differs from that form shown in Figures 1 to 4 inclusive only by the fact that it has a reversal of direction at its center. It will be noticed that the upper half of Figure 6 60 is exactly like Figure 4 and that the lower half of Figure 6 shows the reversal in direction with respect to Figure 4. The cause of this is clear by comparison of Figures 2 and 5, which shows that in Figure 2 the twisting has been from one 65 direction from end to end while in Figure 5 it is from the center outward and thus in two directions.

Figures 7 and 8 and 9 illustrate a modified form in which instead of braiding partially 70 twisted sections back on themselves, two partial-

ly twisted sections are used fitted together and then braided to complete the sling.

As shown in Figure 7, there is one twisted rope section generally like that of Figure 2 in which a rope member 16 is bent to form an initial eye 17 and to form two sections 18 and 19. These are twisted upon themselves to form the loops 20. Below or beyond the point of twisting, the sections are renumbered as 18a and 19a respectively. A similarly made section 21 is bent 10 to make the initial eye 22 and to form members 23 and 24 which upon twisting produce loops 25. Below or beyond the twisted portion these members are renumbered as 23a and 24a respectively. It will be noticed that as these two sections lie together in Figure 7 the direction of the cross-over of one is the opposite of that of the other and this is necessary to produce proper braiding.

As shown in Figure 8, these sections have been 20 put together and braiding may commence. The portions 23a and 24a of the section 21 are braided into the loops 20 of the section 16 and correspondingly the portions 18a and 19a are braided into the loops 25 of the section 21. The sling 25 at the completion of braiding is shown in Figure 9. The loose ends of the sections 23a and 24a may be spliced together and correspondingly the loose ends of the sections 18a and 19a may be spliced together and the sling is thus completed. 30 About the eyes fastening means 26 and 27 may be attached if desired.

I claim:

1. The method of forming a braided rope member, which includes the following steps: 35 taking a rope member doubling it upon itself, twisting it for a portion of its length after doubling and forming thereby a series of loops in the twisted portion, braiding the untwisted ends through the loops so formed and forming a four part braided member.

2. The method of forming a braided rope member, which includes the following steps: taking a rope member doubling it upon itself, twisting it for a portion of its length after doubling and forming thereby a series of loops in the twisted 45 portion, reversing the untwisted ends and braiding them through the loops so formed and forming a four part braided member.

3. The method of forming a braided rope member, which includes the following steps: taking a 50 rope member doubling it upon itself, twisting it for a portion of its length after doubling and forming thereby a series of loops in the twisted portion, braiding the untwisted ends through the loops so formed and forming a four part braided member and splicing the free ends after the completion of the braiding.

4. The method of forming a braided rope member, which includes the following steps: taking a rope member doubling it upon itself, twisting it for a portion of its length after doubling and forming thereby a series of loops in the twisted portion, reversing the untwisted ends and braiding them through the loops so formed and forming a four part braided member and splicing the 65 free ends after the completion of the braiding.

5. The method of forming a braided rope member, which includes the following steps: taking a rope member doubling it upon itself, twisting it for a portion of its length in one direction, after doubling and forming thereby a series of loops in the twisted portion, reversing the 70 untwisted ends and, braiding them through the loops so formed and forming a four part braided member.

5 6. The method of forming a braided rope member, which includes the following steps: twisting a rope member doubling it upon itself, twisting it for a portion of its length in one direction, after doubling and forming thereby a series of loops in the twisted portion, reversing the un-twisted ends and, braiding them through the loops so formed and forming a four part braided member, and splicing the free ends after the completion of the braiding.

10 7. The method of forming a braided rope member, which includes the following steps: taking a single rope member doubling it upon itself, twisting it for approximately one-half its length, after doubling and forming a series of loops in the twisted portion, reversing the un-twisted ends and braiding them through the loops so formed and forming a four part braided member and splicing the free ends after the completion of the braiding.

15 8. The method of forming a braided rope member, which includes the following steps: taking a single rope member doubling it upon itself, twisting it in one direction for approximately one-half its length, after doubling and forming a series of loops in the twisted portion, reversing the un-twisted ends and, braiding them through the loops so formed and forming a four part braided member and splicing the free ends after the completion of the braiding.

20 9. The method of forming a braided rope member which includes the following steps: taking a rope member, doubling it upon itself, twisting it for approximately one-half its length and producing thereby an equal number of oppositely formed cross-overs and forming a series of

loops in the twisted portion, braiding the un-twisted ends through the loops so formed and forming a four part braided member in which the portions braided through the loops are directed oppositely with respect to each other from the center of the resulting member to its ends.

25 10. The method of forming a braided rope member, which includes the following steps: taking a pair of rope members doubling each upon itself, twisting each for approximately one-half its length, braiding two such twisted rope members together and braiding the un-twisted ends of each member through the twisted portions of the other member and forming thereby a four part composite braided member.

15 11. The method of forming a braided rope member, which includes the following steps: taking a pair of rope members doubling each upon itself, twisting each for approximately one-half its length, braiding two such twisted rope members together and braiding the un-twisted ends of each member through the twisted portions of the other member and forming thereby a four part composite braided member, and splicing the free ends of said rope members after the completion of the braiding.

20 12. A unitary rope sling comprising a single rope member, said member being folded upon itself and being arranged in twisted formation for part of its length to provide a plurality of loops, 30 the terminal ends, comprising the un-twisted portion, being folded back upon the twisted portion and each un-twisted end being inserted through each loop from opposite sides thereof throughout the length of the twisted portion.

25 35 JOSEPH M. GARRIS.
